REFRIGERATING AND DISPLAY APPARATUS AND METHOD

Application filed April 26, 1930. Serial No. 447,499.

Our present invention relates more particularly to refrigerator apparatus for storing and dispensing products, particularly food products containing moisture, either frozen or unfrozen, which are exposed to contact of the refrigerating atmosphere, and particularly where the refrigerator is designed to serve also as a show case for displaying the refrigerated products. We have discovered that the refrigerant storage and show case functions each involves certain difficulties and there are many added complications when the two functions are combined.

While all the novel features of our present invention cooperate for the successful combination of both of these functions, it will be evident that these novel features, and certain combinations thereof, may be usefully employed in other relations.

Most of the problems involved relate to preventing deposits of moisture in undesirable places under certain conditions, as for instance, on the glass through which the products are viewed, or on the products themselves; and to preventing the dehydration of the exposed food products, frozen or unfrozen, under other conditions. Both these difficulties increase according as normal temperature in the refrigerated space is low, and particularly where the range is considerably below the freezing point of water, as is necessary for frozen products. Even for higher temperatures attainable with water ice, very rapid convection currents must be utilized to distribute the refrigerant values because the refrigerant itself is so very near the maximum temperature permissible for proper refrigeration. As will be explained, such rapid currents increase the difficulty.

As one factor in the solution of these problems, we employ an intensely cold refrigerant source, preferably solid carbon dioxide, because with the latter merely varying the amount or nature of its insulation enables us to obtain a temperature range near or above freezing; or any lower temperature range that may be desired in case the apparatus is used for frozen products, or as a freezer for unfrozen products. While the gas sub-

limated from the solid carbon dioxide, is very beneficial for fish and some meats, nevertheless, there are other foods and vegetation to which it may be harmful and in the refrigeration of which it may be desirable to prevent even a very low concentration carbon dioxide gas atmosphere from contacting therewith. Moreover, it is difficult to utilize the gas as the refrigerant heat-transferring medium without more or less localizing undesirably low temperatures in the lower part of the refrigerated space. Hence we prefer to employ means whereby the carbon dioxide gas may be excluded from the refrigerated spaces, or may be allowed to enter some or all of them, as may be desired.

Some of the difficulties involved in avoiding deposits of moisture in undesirable places will be evident from the fact that when such a refrigerator is opened for removal or replacement of refrigerated products, even through high level doors, some of the cold air will be spilled out or expelled by the arm of the operator, and warm air and moisture from the exterior will enter the refrigerated space. Any such air even though far from saturated at room temperatures, will become saturated merely by cooling in the refrigerated space. Hence, in most cases, particularly where the normal internal temperature range is low, as in the case of frozen products, a relatively slight cooling of this warm, moist air may cause it to become saturated. Thereafter, further cooling of said air to the normal internal temperature, will be accompanied by release or condensation of a corresponding amount of excess moisture. That is to say, after the incoming air has cooled enough to become saturated and while it is being further cooled down to the normal temperature of the refrigerated space, its moisture content will be deposited upon contact with any surface colder than itself, including surfaces of refrigerated products and inner surfaces of the windows through which the display is viewed, the deposit being either water or frost, according as the condensing surface is above or below freezing point. The more rapid the circulation of convection currents in the refrigerated space, the more like-

ly are these moisture deposits to be made in undesirable places.

While temperature differences causing rapid convection currents may thus cause undesirable moisture deposits whenever the doors of the refrigerator are open during the day time, such currents are also undesirable for other reasons, during nights or holidays, when the refrigerated space remains closed for long periods. Under such conditions, thermo circulation of convection currents tends to become regularized in a single, closed circuit from top to bottom of the entire refrigerated space, the chilled air flowing downward from the coldest spot in the refrigerated space, namely, the refrigerant container. This container is located at a high level in order to avoid over-refrigeration of the lower parts of the space, and such cold down flow will draw in the warmer, moister air in the top of the refrigerated space. Uninterrupted thermo circulation of such convection currents will operate to condense or freeze out all but the minimum moisture content required to saturate the air at the instant when it is coldest, namely, the instant when it is in contact with the refrigerant container. This coldest air flows downward in the refrigerated space and is eventually warmed up to the average temperature of said space, which is much higher than that at the cold spot, and this rise of temperature, being unaccompanied by any increase of the moisture content, will render such air an active drying agent operating objectionably to dehydrate the refrigerated product, even though the latter be frozen.

From the above explanation of our discoveries as to the factors involved, it will be readily understood that an important object of our invention is to modify, minimize and scatter the thermo circulating convection currents in the refrigerated space, thereby minimizing both the dehydration effects last described and also the moisture deposit effects previously described. We accomplish this by arranging highly conducting metallic paths with adequate heat absorbing surfaces extending to relatively remote regions of the refrigerated atmosphere and affording paths of great heat carrying capacity extending from said regions to the refrigerant container. The heat conductor is preferably designed to present approximately uniformly distributed heat absorbing area and to have its heat flow section increasing from the more remote portions to the refrigerant container, so that the heat absorbing areas in the more remote parts have relatively slight temperature differences. Thus, any atmospheric convection currents tending to be set up by such heat absorbing areas will be distributed with approximate uniformity and, being diffused instead of

localized, will be of minimum velocity. Such conductive extensions from the refrigerant container, preferably extend horizontally, preferably at a level substantially below that of the refrigerant container and preferably below the level of any door openings through which cold air can spill out and warm air enter. Such conductive extensions serve not only to directly short circuit, divert and diffuse thermo circulation of the air, but also to greatly raise the temperature of the "cold spot", namely, the lower portion of the refrigerant container. Thus, the temperature differential tending to cause top-to-bottom, end-to-end unitary thermo circulation is decreased and the part of the refrigerated atmosphere below the spill level of the door is provided with distributed, less cold heat absorbing surface adapted to maintain a diffused, unobjectionable convection circulation of the unspilled cold air that always remains in the lower part of the refrigerator.

Another important feature is separating the stored products from the displayed products, by partitioning off the latter in a separate compartment adjacent the show window. Such partition will protect the glass front as well as the displayed goods from direct contact and moisture deposits, when the service door of the storage compartment is opened, even though the spill level of the door opening be below that of the glass front.

Another feature involves utilizing one of the conductive distributing extensions from the refrigerant container as the partition for separating the two compartments. Such a partition being of great heat conducting capacity, tends to absorb heat effectively and more or less equally from both compartments; also in case of unequal temperatures as between the compartments, to absorb more heat from the warmer compartment; also in case of failing supply of the refrigerant, to transfer heat directly from the coldest to the warmest compartment. The latter function may be supplemented by loose joints permitting leakage of atmosphere from the storage to the display compartment. In this connection, it is to be noted that in normal operation, when the service doors are closed, the display compartment always tends to be the warmest because the glass window is practically transparent to and admits radiant heat waves from the exterior, which are trapped within said compartment on the principles well understood in connection with greenhouses. As this compartment must be strongly lighted in order to serve its function of display case, very considerable amounts of radiant heat thus enter and are trapped, particularly where show window lamps and reflectors are employed.

While all of the above improvements tend

to decrease the liability of condensing moisture, either on the inner or the outer surface of the display window, our invention contemplates another expedient for minimizing 5 or preventing this effect. The window, instead of being a single sheet of glass, comprises at least two, and preferably four, parallel sheets with interspaces between them. In and out breathing of moist air in these 10 interspaces may be prevented by perfect packing, but temperature and barometric changes make it difficult to keep such packing perfectly tight, and to avoid this difficulty we provide for circulation of carbon 15 dioxide gas from the refrigerant container into all of said interspaces, preferably serially, by zig-zag flow from one side edge of the inner interspace to the other side edge of the next interspace. The amount of gas thus 20 flowing need not be much greater than required to maintain a continuous outflow to the air from the outermost interspace and this may be adjusted to suit conditions either by 25 a valve in the supply pipe to the first interspace, or by varying the size or level of the outlet of the last interspace, the latter expedient operating by reason of the variable siphon effect determined by the height of the 30 outlet from the outermost interspace.

Our invention also includes a special construction of refrigerant container with attached extension for conductive uniform absorption and conduction of heat from the refrigerated space to the refrigerant. One feature 35 is that the container itself may be located at or above the level of inflow of air when the refrigerated space is open and the principal heat absorbing extension thereof is located below the level at which the cold 40 air can spill out of the refrigerated space. The object of this is to keep this warmer heat absorbing member submerged in the continuously retained, dryer, colder part of the refrigerant atmosphere, while the refrigerant 45 container is in the highest, most variable, warmest, most moist part. With this arrangement, it has been found possible to have practically all of the moisture deposit and resulting insulating effect localized on or 50 immediately adjacent the refrigerant container, while the lower level heat-absorbing area is of such uniform, higher temperature that it collects no moisture in normal operation, even when the service doors are frequently 55 opened.

The above and other features of our invention may be more fully understood from the following description in connection with 60 the accompanying drawings, in which

Fig. 1 is a top plan view of a refrigerating unit embodying our invention, one end being broken away to horizontal section on the line 1—1, Fig. 2;

Fig. 2 is a front elevation with one end

broken away to vertical section on the line 2—2, Fig. 1;

Fig. 3 is a vertical section on the line 3—3, Fig. 2;

Fig. 4 is another vertical section taken on 70 the line 4—4, Fig. 2;

Fig. 5 is a top plan view of a slightly modified form;

Fig. 6 is a vertical section on the line 6—6, Fig. 5;

Figs. 7 and 8 are vertical transverse sectional views corresponding to Figs. 3 and 4, respectively, but showing a modified form;

Figs. 9 and 10 are similar views on a much larger scale, showing details of structure and 80 gas circulation for the show window;

Figs. 11, 12 and 13 are large detail views 85 of a preferred form of the solid carbon dioxide container and its integral heat conducting extension, Fig. 11 being the plan view, Fig. 12 an end elevation, and Fig. 13 a front elevation with the container shown in vertical section.

In these drawings, the refrigerator case is 90 indicated as comprising outer and inner gas-tight shells 1 and 2, affording heat insulating interspaces. The shells may be of enameled sheet metal, commonly employed in modern refrigerators, and the interspaces may be filled with insulating material, kapok 3 being 95 preferred for the side walls and solid material such as cork 5 for the bottom. In any case, the insulating material in the side walls should be sufficiently porous to permit saturating it with carbon dioxide gas, while the material in the bottom should be firm enough to support the desired loads on the bottom of the inner shell.

The shape of the refrigerator and the general disposition of its operating parts is somewhat the same in all the figures. As shown 100 in Figs. 1 to 4, the structure is relatively long and narrow, and has a central transverse partition separating it into two parts and in 105 each part the elements are symmetrically disposed with respect to the plane of said partition. In each half, the front elevation shows a vertically disposed front wall A, a rearwardly inclined display window B through which may be seen a door C affording 110 access to the display space behind the window. The top plan view, Fig. 1, shows the same rearwardly slanting display window B, and in addition the high level closure or hatch D, through which the refrigerant 115 container is charged, and the closure E at a lower level through which access is had to the storage space F (see Fig. 4).

With this arrangement of parts, it will be 120 evident that with a refrigerated atmosphere consisting of air only, an ordinary uninsulated metal container of carbon dioxide, located at a high level, upper corner of the space would naturally tend to establish high velocity convection currents flowing downwardly 125 130

from the container, lengthwise of the bottom, upwardly at the central partition and back under the upper wall or roof. Moreover, the upward circulation would be largely adjacent the outer walls which are most exposed to heat from the exterior. With such idea of the normal convection currents under conventional conditions, the novelty and effectiveness of the various features constituting our invention, may be more easily understood and appreciated.

In the upper part of the case, preferably in the remote end of each section, is fitted the refrigerant container 7, which is open at the top for filling, closure D preventing entrance of outside air. The gas evolved from the solid carbon dioxide in the container being preferably kept out of the refrigerated space, is disposed of in various other ways, as by discharge into the kapok insulation through vent 14, discharge through the joints of the cover D, etc. In Fig. 2, the refrigerant container is shown as surrounded by insulating material on three sides, so that only the bottom and front are exposed to the air circulation in the refrigerated space. Even these surfaces are not excessively cold because of the massive large area heat collecting extensions designed and operating on the principles heretofore explained. In the form shown in Figs. 1, 2 and 3, the extension 8 is in the form of a wide vertical plate integral with the container 7, extending below the same, and laterally along the wall, in operative heat absorbing relation to the atmosphere, to remote points in the refrigerated space.

The container and its integral extension are made of comparatively thick metal of high heat conductivity such as aluminum. The walls of the container taper from a thin upper edge down to a thick bottom, and the lateral extension tapers from great thickness at the line of union with the bottom of the container, down to relative thinness at the remote end. The effective heat absorbing surface of this member may be varied either by making it of greater or less width or providing it with fins, as shown. Preferably, it is bolted to the rear wall as shown, so that only the front surface is effective for absorbing heat from the atmosphere.

The cross section and taper with reference to the heat absorbing area and the temperature to be maintained in the refrigerated space may be designed for a reasonable approximation of uniform temperature throughout the entire heat absorbing area of the extension, for the above described purpose of correspondingly distributing and rendering uniform the local convection currents which may be set up thereby. Obviously, the wider the distribution and the greater the uniformity of such currents, the less will be their velocity at any one point.

It is to be noted also that the down-leg of any such weak circulation will be in opposition to the natural upflow which would otherwise tend to occur adjacent the exterior wall through which the heat penetrates from the exterior. Because of the low level of this horizontally extending heat absorber, it will tend to operate only on the body of cold air which remains below the spill level of the service door, even when the latter is open. All of these factors contribute to enfeeble and confuse thermo circulation to a degree approximating stagnation so far as concerns danger of depositing water or frost on the products during times when the service doors are frequently opened or objectionably dehydrating said products when the doors are closed for long periods.

Container 9 may have a cock x, for discharging gas directly into space F.

While it would be possible to have duplicate heat absorbing extensions for both walls of the refrigerated space, we prefer to secure to the front wall 11 of the refrigerated container a heavy metallic heat absorber and conductor which also serves the purpose of a partition 12, closing off a separate compartment in which products may be specially arranged for display instead of having the display consist of the stored products in the storage space. While this partition member might be cast integral with the front wall of the container and might be of cast iron or other metal, we prefer to make it of sheet or plate aluminum. Although only one sheet is shown, it is easier to bend the partition to the required curvature and yet have it of desired thickness, by employing two thicknesses, each, say, $\frac{1}{8}$ inch, making a total thickness of, say, one-quarter inch. If bolted tightly to the wall 11, this will serve as an effective heat collector for the refrigerant container in addition to serving as an equalizer of temperatures between the compartments when either one tends to be warmer than the other. It may be supplemented by an integral extension 8a, from the bottom of 9.

The window is of the multiple pane type, having any number of panes 18, the panes being spaced apart to provide the carbon dioxide gas circulation spaces 19. At the upper side of the window is a pipe 20 connecting the innermost space 19 with the refrigerant container. This pipe has a three-way valve at some point in its length to provide for venting gas into the display section 21 or to the spaces 19 or to both of them simultaneously. The gas is led from the refrigerant container through the pipe 20 and vented into the innermost space 19 at the point 22. Carbon dioxide gas being approximately 50% heavier than air will fall to the bottom of the space and flow through the by paths 23, located at the end opposite 22, the gas in its downward path and longitudinal flow will become

warmer than the freshly evolved gas admitted at 22, the new gas entering the innermost space being heavier than the gas already in there which has had time to warm up, said 5 warm gas will naturally be forced up through the next space 19 and may be vented to the atmosphere through the vent 24 which is located at the opposite end from the by paths 23. The arrangement of intake and outlet 10 and communications between the spaces so as to be alternating between the ends of the window, insures a complete circulation of the cold dry carbon dioxide gas between the window panes. When the gas is circulated in 15 this manner we have the coldest gas next the innermost pane which of course is the coldest and as the gas proceeds toward the exterior vent each successive pane with which it comes in contact is warmer than the preceding one, 20 consequently there is no abrupt or sudden fall of temperature but a slow, even fall, whereby when it reaches the outermost pane, the gas is so near atmospheric temperature, that it cannot chill the pane enough to cause it to 25 condense moisture on its outer surface. This arrangement has the further advantage that the constant supply and consequent continuous outflow of dry, progressively warmed carbon dioxide gas prevents any inbreathing 30 of moisture and maintains the respective outer and inner surfaces free of frost and moisture.

We have found that the most efficient operation can be obtained by making the heat 35 conducting parts of suitable thickness and by placing the septum 12 in desired conducting relation to the wall 11 of the refrigerant container, according to size of the compartment 21. A rack or shelf either permanently 40 attached or removable may be placed in the compartment 21 to hold the products to be displayed. A substantial gas-tight door or closure 25 permits of access to the space 21, without opening the service door E. This 45 construction provides a substantial air-tight display space which is not exposed to inlet of outside atmosphere at any time except when the same is either being dressed or undressed for display purposes, consequently 50 there will be very little change of temperature within the space at any time.

The storage or dispensing space F is preferably much larger than the display section and being subject to a more or less frequent 55 intake of outside temperature, due to the opening of the doors, it has been found necessary to provide a much greater heat absorbing area within this space than is required for the section 21. This difficulty is overcome 60 by adding to the high heat transfer surface 9, the depending and longitudinally extending radiator or fin section 8.

It can readily be seen that our invention 65 provides a plurality of refrigerated spaces, each maintained so that there is no direct

communication with the other, and a container of refrigerant, preferably solid carbon dioxide, in high heat conducting relationship to near and remote portions of the refrigerated spaces, but without using the gas from the solid carbon dioxide as a part of the atmosphere of the refrigerated space, unless and only to the extent desired; and at the same time minimizing convection currents and objectionable deposits of moisture and 70 dehydration of products. 75

If the case is of sufficient size, there can be a unit in each end as clearly shown in Figs. 1, 2 and 5, having partitions 26 to divide the case in sections, thus facilitating defrosting 80 of the case, when the same becomes necessary, by permitting one side of the case to continue in operation while the other side is being defrosted. The troughs 27 are provided to catch or draw off water when the defrosting 85 is being done.

By reference to Figs. 1, 2 and 4, it will be evident that a work space or table 28 is provided and obscured from view by the two refrigerant bunkers on the ends and the display section in the front. Access to the storage space is had through the openings 29 which are closed by the doors or plugs E, of any conventional type. 90

In Figs. 5 and 6, a slight modification is shown. In this construction, the work table 28 is supported, above the top of the casing 28, the latter being inclined and provided with doors 29c adapted to slide beneath said table. This increases the height of the storage chamber and makes the entrance, 25b, to the display space 21b, through the storage chamber 10b. This modification has the advantage over the first construction of never permitting direct inflow of outside atmosphere to the display space as is the case of the construction first described. The entrance 25b, with its closure 25c, is conveniently placed with reference to the opening 29b which is closed by the door 29c to permit of easy access to the interior of the display space and when the door 25b is opened, instead of outside atmosphere entering the display space as would be the case in Figs. 1, 2, 3 and 4, the colder, dryer atmosphere from within the storage chamber 10b will enter, thus causing much less disturbance of the temperature and moisture conditions within the display space. 100

As it is more important to supply carbon dioxide gas to the window in front of the display section than to the insulation, we find it better to place the vent 24 as low or lower than the vent 14, as in Fig. 3. This throws the intake 20 below the vent 14, thereby insuring a full supply of carbon dioxide gas to the spaces 19, before the gas level rises high enough to overflow opening 14. 110

The form shown in Figs. 7 to 13 contains 115 all of the elements found in the preceding

figures, but with certain changes which when tested out in the actual working devices are found to be of considerable advantage.

The display compartment 21 α is of less vertical height and greater thickness and has a larger door 25 α . Moreover, the service closure E α is pitched at a much higher angle and made larger, thereby making it easier to reach into the display compartment. The foregoing are all advantages so far as concerns mere practical use of the apparatus, but there are other features which are functionally important.

The above changes in size and proportion 15 greatly reduce the volume of the higher, warmer upper part of the atmosphere within the storage chamber. Moreover, as shown in Fig. 8, one side of the refrigerant container is laterally exposed to this part of the atmosphere. Furthermore, the heat collecting extension 8 α , instead of extending laterally on the same level as the bottom 9 α of the container, is brought down to a much lower level, as will be evident from Figs. 12 and 25 13; also the bottom of the container and its junction with the heat collector is very much more massive.

This combination of changes, as actually tested out in practice, has the advantage that 20 the exposed end and lower part of the refrigerant container does all of the freezing out of the water so that in normal operation there is no accumulation of frost or ice on the low level heat collector 8 α . Consequently, while frost or ice collecting on the container affords gradually increasing insulation therefor, the heat absorbing surface of 25 8 α remains unmodified and in full operation. Moreover, the height and narrowness of the upper space where the freezing out takes 30 places makes it more difficult for cool air in the bottom of the storage space to join in a complete top to bottom thermo circuit, the upflow into this region as well as return flow to the refrigerant container being deadened and diffused by heat absorption due to the relatively close juxtaposition of the cold heat absorbing surfaces 8 α and 12 α which extend along this part of the natural return path of any top-to-bottom, end-to-end, thermo circulation. See Fig. 8.

While the dimensions and proportions of parts of the apparatus may be varied within wide limits, it may be noted that in a special case a refrigerator proportioned, constructed and successfully operated as last above described, the refrigerant container 7 α was of cast aluminum or aluminum alloy and of about 1 cubic foot capacity, with the side walls having a thickness of approximately one-half inch at the top, increasing to one inch or more at the bottom, and the horizontal bottom wall was approximately the same one inch thickness at the base of the outer wall 11 α , increasing to one and three-quar-

ters inches at its junction with the integral depending bracket-like extension. The latter tapers downward to one inch at its junction with the horizontally extending heat collector 8 α . The latter is approximately three feet, four inches long by eight and one-half inches high, and is tapered in thickness from one inch adjacent the refrigerant container to three-eighths inch at the remote end, the latter representing the minimum thicknesses, exclusive of the ribs.

The above dimensions, proportions, tapers, etc., may be varied widely in order to more accurately suit the same or different conditions of use, particularly different dimensions of the refrigerated space and different temperature ranges of desired normal operation, but it is understood that all such adaptations should be governed and determined by the principles and functionings heretofore explained.

It must not be inferred from the foregoing that the novel principles of our present invention require any great exactitude of proportioning or design of the apparatus in order to get entirely satisfactory practical results as concerns avoiding undesirable moisture deposits and dehydration of products. In this connection, it may be well to note as concerns any apparatus embodying these principles, the normal temperature range of refrigeration can be easily controlled, merely by varying the insulation of the solid carbon dioxide within the container. For instance, in apparatus as above described, with a supply of solid carbon dioxide entirely uninsulated and resting upon the aluminum bottom, a very uniform, low temperature could be maintained below zero, but merely interposing a sheet of wrapping paper for the solid carbon dioxide to rest upon, will cause the apparatus to operate with equal uniformity at or near 20° above zero. Additional insulation, wrappings or paper containers for the solid carbon dioxide may be employed to predetermine desired above freezing temperatures.

Obviously, additional heat collecting extensions can be cast integral with the same refrigerant container, as for instance, the partition member 12 α , could be so cast; also where two compartments are not desired, the second extension could be of the same size and shape as 8 α and symmetrically disposed parallel with it on an opposite wall of the refrigerated space.

In connection with the functionings of the refrigerant container and heat collector structure, such as above described, it is to be remembered that the great heat storage capacity of the aluminum or other metal is proportional to the mass as well as to the specific heat of the metal. In the present connection, heat storage capacity is the same thing as refrigerant storage capacity, that is

to say, the greater the mass of the metal, the more heat units it must absorb in order to raise its temperature one degree, and the more massive are the parts intervening between the warm regions and the cold regions, the more quickly and effectively can any one region tap the refrigerant reservoir capacity of any other region, either for warming or for cooling.

From the above, it will be evident that the total mass of the entire system is important, and that the massiveness toward and at the bottom of the refrigerant container is important. These heat storage and conductivity relations of parts of the system, tend to maintain constant temperature in each part of the system; and changes of temperature of the atmosphere in any part of the system tend to equalize, slow down and minimize changes of rate of the evaporation of the solid carbon dioxide.

Hence, while the refrigerant container and heat collector structures such as above described could be made of metal of less heat conductivity than aluminum, as for instance, cast iron, nevertheless, for equal conductivity and storage capacity, the thicknesses, particularly of the heat conducting extensions, would have to be greatly increased. For instance, if the partition wall 12 α were of cast iron, its thickness might be, say $\frac{5}{8}$ inch to $\frac{3}{4}$ inch. Even so, its heat transfer rate, particularly as between the two compartments, would be less than that of the quarter inch aluminum.

Figs. 7 and 8 show the window B α with lamps 30 and reflectors 31 for lighting the display space 21 α , tending to warm the upper part of the window and to radiate heat through the glass into said space 21 α . The window has four sheets of glass 18 α , affording three interspaces 19 a , 19 b , 19 c , and Figs. 9 and 10 show that the first space 19 a , and second space 19 b , may be serially connected at the bottom, as at 23 α . The third or outer space, 19 c , is serially connected through 23 α , so that it is supplied only by overflow from the warmest air in the intermediate space 19 b . This outer space, 19 c , can be tapped at the bottom, as shown at 24 α , thereby making it a definite downflow leg of the circulation. In such case, the escaping gas will be drawn from the lowest part of the interspace where the coldest part of the gas gravitates, thereby avoiding possibility of a cold spot and possible condensation on the lower part of the outer surface of the outermost pane. However, the gas overflowing into this third outermost space, from the top of the second interspace is likely to be so warm that even the coldest of it is not likely to cause such condensation even on the lower part of the outer surface of the outside glass. Consequently, it is possible to plug the lower outlet 24 α and provide a top outlet as indicated at 24 y ; in which case,

this space becomes a mere pocket; or the outlet may be at any intermediate level, as indicated at 24 z . In the latter connection, it is to be noted that when the gas supply and outlets are such as to maintain the interspaces at approximately atmospheric pressure, the flow of gas will be controlled by the difference in altitude between the inlet 22 α and the outlet 24 α , or 24 z . In such case, the flow of gas will be a maximum when the lowermost outlet 24 α is open, and correspondingly less when 24 α is plugged and 24 z is open. When 24 α and 24 z are closed and 24 y open, the rate of flow will depend on the difference in temperature of the gases in the first and second spaces. While voluminous flow can always be forced by pressure of the gas at the inlet 22 α , the distributed, optional outlets, at different levels, are preferable for controlling slow rates of flow through the interspaces to give the gas time to warm up before it reaches the outermost glass.

While the above described continuous flow of carbon dioxide gas through the successive interspaces between the panes will have the advantages above described, it will be understood that the insulating quality of the gas even when warm and stagnant is of great value and, if desired, the outlet may be plugged after the interspaces have been freed from air and moisture and have been filled with the pure dry gas. In such case, the connection to the source of gas may be retained so that any in and out breathing due to temperature or barometer changes will consist of pure gas. Or, in certain cases where the construction and packing of the glass is perfectly tight so as to withstand expansion or contraction without inbreathing, the interspaces may be purged of air and moisture, filled with gas and plugged.

We claim:

1. In a refrigerating apparatus the method of preventing moisture deposits, by means of the refrigerant, on refrigerator windows consisting of parallel plates with interspaces, which method includes sublimating solid carbon dioxide and discharging dry gas therefrom into the inner, coldest interspace and conducting the same serially through the successive interspaces, to the exterior atmosphere.

2. A refrigerator apparatus comprising an insulating casing, having a high level service door, in combination with a high level container of solid carbon dioxide having a massive metal wall and a massive, highly conducting heat collector extending below the level of said container, to horizontally remote regions of the refrigerated atmosphere and affording heat flow paths of great heat carrying capacity, extending from said regions to said refrigerant container, a wall of said casing having a display window and said heat collector being formed as a par-

tion closing off a display space adjacent said window.

3. A refrigerator apparatus comprising an insulating casing, having a high level service door, in combination with a high level container of solid carbon dioxide having a massive metal wall and a massive, highly conducting heat collector extending below the level of said container, to horizontally remote regions of the refrigerated atmosphere and affording heat flow paths of great heat carrying capacity, extending from said regions to said refrigerant container, a wall of said casing having a display window and said refrigerant container having a second highly conducting heat collector formed as a partition between said service door and said window separating a storage space accessible through said door, from a display space adjacent said window.

4. A refrigerator comprising an insulating casing with a window having a plurality of panes affording insulating interspace, a thick wall of good conducting metal opposite said window and a container of solid carbon dioxide outside of said wall absorbing heat from said wall through an all-metal path to effect refrigeration of said chamber, the gas sublimated from said solid venting to the exterior partly through the interspace between said window panes thereby further heat insulating the interior of the refrigerator.

5. A refrigerated case having walls of porous material between inner and outer surfaces substantially impermeable to carbon dioxide gas, a solid carbon dioxide container in the upper part of said case, a storage chamber below said carbon dioxide container, a display section in front of said solid carbon dioxide container and said storage chamber, and a communication between said solid carbon dioxide container and said porous material whereby carbon dioxide gas from said container is led to and permeates said porous material.

6. A refrigerated case enclosing a solid carbon dioxide container, a storage chamber and a display section, a spaced apart multiple pane window in front of the display section and a conduit to carry carbon dioxide gas from said solid carbon dioxide container and vent the same in a space between the said window panes thereby further heat insulating the interior of the refrigerator.

7. A refrigerated case comprising a solid carbon dioxide container, a storage chamber and a display section, a spaced-apart multiple pane window in front of said display section, forming a plurality of spaces between said panes, and a conduit to carry carbon dioxide gas from said solid carbon dioxide container and vent the same in a space between said window panes, said spaces being interconnected whereby carbon dioxide gas flows in a tortu-

ous path through said spaces between said paths thereby further heat insulating the interior of the refrigerator.

8. A refrigerated case comprising outer insulated walls, a solid carbon dioxide container, a storage chamber, a display section and a spaced apart multiple pane window in front of said display section and a means whereby carbon dioxide gas sublimated from said solid carbon dioxide is permitted to flow between said panes but is prevented from entering the refrigerated spaces thereby further heat insulating the interior of the refrigerator while at the same time preventing the gas from entering the refrigerated spaces.

Signed, at New York, in the county of New York and State of New York, this 24th day of April, A. D., 1930.

CHARLES L. JONES.
HOWARD S. McILVAIN.
